(74) Attorney, Agent, or Firm—Banner & Witcoff, Ltd.

(57) **CLAIM**

The ornamental design for an insulated food tray bulk condiment holders, as shown and described.

DESCRIPTION

FIG. 1 is an isometric view of an insulated food tray bulk condiment holders showing our design;

FIG. 2 a top plan view thereof;

FIG. 3 a bottom plan view thereof;

FIG. 4 a front elevational view thereof; and,

FIG. 5 a side elevational view thereof.

The broken line showing is for illustrative purposes only and forms no part of the claimed design.
